US00D747378S

(12) **United States Design Patent**
Hassan et al.

(10) **Patent No.:** **US D747,378 S**
(45) **Date of Patent:** **** Jan. 12, 2016**

(54) **ADAPTER SLEEVE FOR AN ARC WELDING APPARATUS**

(71) Applicant: **Victor Equipment Company**, Denton, TX (US)

(72) Inventors: **Khalid Hassan**, Denton, TX (US); **Glenn K. Redding**, Flower Mound, TX (US)

(73) Assignee: **Victor Equipment Company**, Denton, TX (US)

(**) Term: **14 Years**

(21) Appl. No.: **29/508,004**

(22) Filed: **Oct. 31, 2014**

(51) LOC (10) Cl. **15-09**

(52) U.S. Cl. **USPC .....** **D15/144**

(58) **Field of Classification Search**

USPC D8/29.1, 30; D15/144, 144.1, 144.2; 219/70, 137.44, 137.52

CLAIM

The ornamental design for an adapter sleeve for an arc welding apparatus, as shown and described.

DESCRIPTION

FIG. 1 is a perspective view of the adapter sleeve for an arc welding apparatus;

FIG. 2 is another perspective view;

FIG. 3 is a side view;

FIG. 4 is another side view;

FIG. 5 is a front view;

FIG. 6 is a rear view;

FIG. 7 is a top view; and,

FIG. 8 is a bottom view.

1 Claim, 8 Drawing Sheets
